HARRY H. STOUT, OF NEW YORK, N. Y., ASSIGNOR TO GENERAL CHEMICAL COMPANY,
OF NEW YORK, N. Y., A CORPORATION OF NEW YORK.

RABBLE-ARM.

1,191,848.

Specification of Letters Patent. Patented July 18, 1916.

Application filed December 4, 1913. Serial No. 804,559.

To all whom it may concern:

Be it known that I, HARRY H. STOUT, a citizen of the United States, and a resident of the borough of Manhattan, city, county, 5 and State of New York, have invented a certain new and useful Improvement in Rabble-Arms, of which the following, taken in connection with the accompanying drawings, is a specification.

10 My invention relates to roasting furnaces, particularly to ore-roasting furnaces of the general type shown and described in United States Letters Patent to John B. F. Herreshoff, Number 616,926, dated January 3, 1899, 15 and has for its object the production of rabble arms and securing means for said arms of such furnaces, which, among other advantages, shall be easy of manufacture and of application to and removal from the furnace structure and shall be of particular value in withstanding the heat and stresses of operation in the furnace.

In the accompanying drawings which illustrate an embodiment of my invention, 20 Figure 1 shows such embodiment in longitudinal vertical section, and Fig. 2 is a cross section thereof on the line 2—2 of Fig. 1.

The central rotatable shaft of the furnace is formed in any suitable manner so as to 25 have a central passage and an annular passage surrounding said central passage. Where my rabble arm is to be applied to the central shaft, the latter is provided with apertures in the inner wall 3 inclosing the 30 central passage and the outer wall 4 inclosing the annular passage. These apertures are respectively preferably surrounded and defined by annular flanges 3' and 4' and are of a contour to correspond with the outer contour 35 of the portion of the arm members adapted to be inserted into them so that the external arm member 5 will fit nicely within the flange 4' and the internal arm member 6 will in like manner fit within the flange 3', 40 of the joints made by these members and the flanges being telescopic joints. When thus positioned the rabble arm will extend outwardly from the rotary shaft so as to sweep over the furnace hearth below the arm, the 45 internal member being within the external

member and being supported thereby along substantially its entire length.

Both the internal and external members are preferably cylindrical pipes of wrought iron or steel, the former being of a diameter 55 slightly greater than the radius of the latter. The external tube 5 is provided at its outer end with a closure 7 which may be of any suitable construction and at a distance from said end with a stop rod 8, extending preferably diametrically through the tube, its ends being riveted or otherwise suitably secured to the tube walls. The outer end of the internal tube 6 is adjacent the stop 8 which limits outward movement of the tube 60 6 relatively to the external tube 5. The external and internal members of the arm are not secured together but are independent of each other. Thus the external member may expand without affecting the internal member 65 in any way and the stop 8 thereon is so positioned that the internal member while free to move is prevented from slipping out of its joint.

The flange 4' is provided with an opening 75 in its upper portion and the external tube 5 is provided with a corresponding opening near its inner end adapted to be placed in alignment with the opening in the flange. When so positioned a lock pin 9 is inserted 80 into the openings so as to lock the arm and the rotary shaft in proper relationship. The pin 9 is provided with a head 9' of a larger diameter than the pin shank and with a stop shoulder 9'' at a distance from the 85 head, to limit the movement of the pin into the openings and to provide a space between the head 9' and the flange 4' into which space the end of a suitable tool may be inserted for the purpose of withdrawing the 90 pin from the opening in the arm member 5 and thus permit of the removal of the arm from the rotary shaft. This tool may be provided with a claw end having cam surfaces for engaging the underside of the 95 head 9' and may be of such a length as to be operated through the usual furnace doorways through which the rabble arms are inserted and withdrawn.

To position and secure the arm properly, 100

the shaft is rotated until the apertures therein are opposite one of the furnace doorways. The external member 5 of the arm, carrying the internal member 6 thereof, is moved through the doorway and the inner ends of the members 6 and 5 are moved into position within the flanges 3' and 4' respectively. Of course, the member 6 may be inserted before and independently of the member 5. The pin 9 is now placed in the opening of the flange 4' and the member 5 is rotated until the opening therein alines with the flange opening and the pin 9 drops into place. For the purpose of facilitating the process of assembling, the riveted end of the rod 8 and the opening in the member 5, are preferably located in the same diametral plane so that the openings in the flange 4' and the member 5 may be readily placed in alinement by rotating the member 5 until the visible end of the rod 8 alines with the pin 9.

The external member of the arm may be provided with rabble teeth in any suitable fashion so that during the rotation of the shafts the teeth will agitate and propel the material on the hearth. For cooling the rotary system, a cooling fluid such as air, is caused to traverse the central shaft and the rabble arms. The cooling medium is preferably forced into the axial chamber of the shaft formed by the wall 3, from which it passes through the arm member 6 and from the outer end of this member into the end chamber 10 of the external arm member 5; from this chamber the fluid passes through the member 5 outside of the member 6 and is discharged therefrom into the annular chamber of the shaft between the walls 3 and 4 thereof.

The rod 8 is of relatively small size and the chamber 10 is of large capacity; moreover, the capacity of the inner member is substantially the same as that of the effective portions of the external member. The result is that a large volume of cooling fluid moves with a substantially constant velocity through the arm without being obstructed to an appreciable extent. In this way a maximum volume of fluid traverses the arm and a maximum cooling is effected. The wrought iron or steel pipes constituting the arm are stronger and lighter and less fragile than the usual cast iron arm and so are less apt to become broken or bent during the operation of the furnace.

The removal of the arm members is easily accomplished by drawing up the pin 9 and then pulling the members out of their sockets. It will be readily seen that even when the members have become bent, their removal is equally easy; this would not be the case if the joints were, for example, screw-

threaded instead of telescopic. The joints between the pipes and the shaft flanges are loose joints of extremely simple construction, the meeting surfaces of these parts being merely machined so as to have an easy fit. By reason of the fact that the arm is composed of separate members which are not bound together at any point, these members are free to expand relatively to each other without danger of shearing. Moreover in case the external member in some way becomes useless, as when it is worn out, a new member can be substituted for the old one without disturbing the internal member.

I claim:—

1. In combination, a double-walled shaft, a rabble arm comprising external and internal pipes, the internal pipe being of a diameter greater than the radius of the external pipe and being located in and supported substantially along its entire length by the external pipe, the inner end of the internal pipe being connected with the inner wall of the double-walled shaft by a telescopic joint and the delivery end of the internal pipe being located adjacent to the outer end of the external pipe, and a stop to prevent outward movement of the internal pipe as a whole.

2. A rabble arm construction comprising an external member, an internal member independent of said external member, the outer end of said internal member being spaced from the outer end of said external member, and a stop connected with said external member to limit the outward movement of said internal member relatively to 100 said external member.

3. In combination, a double-walled shaft, a rabble arm comprising an external member connected with one of the walls of said shaft by a telescopic joint, an internal member connected with the other of said shaft walls by a telescopic joint, said internal member being movable independently of said external member and the outer end of said internal member being spaced from the outer end of said external member, and a stop connected with said external member to limit the outward movement of said internal member relatively to said external member.

4. In combination, a double-walled shaft, a rabble arm comprising an external member connected with one of the walls of said shaft by a telescopic joint, the portions of said shaft and said member constituting such joint being provided with alined openings, a pin extending into said openings to secure said shaft and said member together, an internal member connected with the other wall of said shaft by a telescopic joint, said internal member being movable independently

of said external member and the outer end of said internal member being spaced from the outer end of said external member, and a stop connected with said external member
5 to limit the outward movement of said internal member relatively to said external member.

In testimony whereof, I have hereunto set my hand in the presence of two subscribing witnesses.

HARRY H. STOUT.
